UNITED STATES PATENT OFFICE

127,802

DESIGN FOR A SUGAR-CANE TRUCK

John G. Holmstrom, Seattle, Wash., assignor to
Kenworth Motor Truck Corporation, Seattle,
Wash., a corporation of Washington

Application January 17, 1940, Serial No. 89,525

Term of patent 14 years

To all whom it may concern:

Be it known that I, John G. Holmstrom, a citizen of the United States, residing at Seattle, in the county of King and State of Washington, have invented a new, original, and ornamental Design for a Sugar-Cane Truck, of which the following is a specification, reference being had to the accompanying drawings forming a part thereof.

In said drawings:

Figure 1 is an elevational view from the left

side illustrating a sugar-cane truck showing my new design.

Fig. 2 is an elevational view from the front.

Fig. 3 is an elevational view from the rear.

Fig. 4 is a top plan view; and

Fig. 5 is a side perspective view thereof.

I claim:

The ornamental design for a sugar-cane truck, as shown.

JOHN G. HOLMSTROM.
